Primary Examiner—Alan P. Douglas*Assistant Examiner*—Susan Moon Lee(74) *Attorney, Agent, or Firm*—Van Dyke, Gardner, Linn & Burkhart, LLP(57) **CLAIM**

The ornamental design for a game feeder, as shown and described.

DESCRIPTION

FIG. 1 is a right side perspective view of a game feeder showing my new design, with a mounting detent, pole, attachment plate, and bolts shown in dotted lines not forming a part of the invention;

FIG. 2 is a perspective view of the left side of the game feeder of FIG. 1;

FIG. 3 is a right side perspective view of FIG. 1;

FIG. 4 is a left side perspective view of FIG. 1;

FIG. 5 is a top plan view of FIG. 1;

FIG. 6 is a bottom perspective view of FIG. 1;

FIG. 7 is a front perspective view of FIG. 1; and,

FIG. 8 is a back elevation of FIG. 1.
